XANTHOGEN FORMATES

Arthur H. Fischer, New York, N. Y., assignor to
Minerec Corporation, New York, N. Y., a corpora-
tion of New York

**No Drawing. Application June 2, 1948,
Serial No. 30,741**

5 Claims. (Cl. 260—455)

1

This invention relates to the production of new organic compounds and has for an object the provision of novel xanthogen formates. More particularly, the invention contemplates the provision of novel alkyl xanthogen formates. An object of the invention is to provide xanthogen formates having a saturated alkyl radical as a substituent of the xanthogen moiety and a radical as a substituent of the formate moiety which is more polar than an ethyl group would be if present as such a substituent.

The reagents of the invention may be produced by reacting alkyl xanthates comprising saturated alkyl radicals with chloroformates comprising unsaturated organic radicals in accordance with the following equation:

In the formulas set forth above, R is a saturated alkyl radical containing not less than two carbon atoms and R' is an unsaturated organic radical comprising a double bond or an unsaturated organic radical comprising a triple bond.

The compounds of the invention are suitable for various uses. They may be employed with particular advantage as mineral collecting agents in the concentration of minerals by froth flotation. Among the compounds found most suitable for use in such concentration processes are: ethyl xanthogen allyl formate, ethyl xanthogen propargyl formate, ethyl xanthogen methallyl formate, propyl xanthogen allyl formate, propyl xanthogen propargyl formate, propyl xanthogen methallyl formate, butyl xanthogen allyl formate, butyl xanthogen propargyl formate, butyl xanthogen methallyl formate, amyl xanthogen allyl formate, amyl xanthogen propargyl formate, amyl xanthogen methallyl formate, hexyl xanthogen allyl formate, hexyl xanthogen propargyl formate, and hexyl xanthogen methallyl formate.

Compounds of the above types may be illustrated by the following structural formulas:

in which R is a saturated alkyl radical containing from two to six carbon atoms having as the substituent of the xanthogen moiety and in which an unsaturated allyl radical is having as the substituent of the formate moiety;

$$\text{RO}-\underset{\text{S}}{\underset{\parallel}{\text{C}}}-\text{S}-\underset{\text{O}}{\underset{\parallel}{\text{C}}}-\text{O}-\text{CH}_2\underset{\text{CH}_3}{\underset{|}{\text{C}}}=\text{CH}_2$$

in which R is a saturated alkyl radical contain-

ing from two to six carbon atoms disposed on the xanthogen side and in which an unsaturated methallyl radical is disposed on the formate side; and

in which R is a saturated alkyl radical containing from two to six carbon atoms disposed on the xanthogen side and in which an unsaturated propargyl radical is disposed on the formate side.

The use of the compounds of the invention for the concentration of minerals is described and claimed in my copending application Serial No. 30,742, filed June 2, 1948.

The following example illustrates a method of preparing compounds in accordance with the invention:

60.2 grams of allyl chloroformate were added rapidly with constant stirring to a solution of 94.1 grams of potassium butyl xanthate in 400 cc. of water at a temperature of about 25° C. The reaction proceeded slowly with the production of an oily liquid product. After stirring three hours, the oily product was separated, washed, and dried in vacuum. The yield was 110.2 grams, equivalent to 94% of theoretical yield in accordance with the following equation:

35 The oily product was substantially pure butyl xanthogen allyl formate, as indicated by the following data:

	By Analysis	Theoretical
Percent sulfur.....	27.45	27.50

45 Xanthogen formates containing other saturated alkyl radicals and other unsaturated organic radicals may be produced by the same procedure or by similar procedures when employing xanthates and chloroformates containing such other radicals.

I claim:

1. A compound having the structural formula—

55 in which R is an alkyl radical containing from

two to six carbon atoms and R' is an unsaturated hydrocarbon radical containing not more than four carbon atoms.

2. A compound having the structural formula—

in which R is an alkyl radical of the group consisting of ethyl, propyl, butyl, amyl, and hexyl, and R' is an unsaturated hydrocarbon radical containing not more than four carbon atoms.

3. A compound having the structural formula—

in which R is an alkyl radical of the group consisting of ethyl, propyl, butyl, amyl, and hexyl.

4. A compound having the structural formula—

in which R is an alkyl radical of the group consisting of ethyl, propyl, butyl, amyl, and hexyl.

5. A compound having the structural formula—

in which R is an alkyl radical of the group consisting of ethyl, propyl, butyl, amyl, and hexyl.

ARTHUR H. FISCHER.
